[57] **CLAIM**

The ornamental design for a wheel bracket for in line roller skate boot, as shown and described.

DESCRIPTION

FIG. 1 is a side elevation view of the bracket showing our new design, the other side being a mirror image thereof;

FIG. 2 is a left end view of the bracket shown in FIG. 1;

FIG. 3 is a right end view of the bracket shown in FIG. 1;

FIG. 4 is a top plan view of the bracket shown in FIG. 1; and,

FIG. 5 is a bottom plan view of the bracket shown in FIG. 1.

The broken line showing of the boot and wheels in FIG. 1 is for illustrative purposes only and forms no part of the claimed design.

FIG. 1

FIG. 2

FIG. 3
